UNITED STATES PATENT OFFICE.

WILLIAM INGALLS, OF MOBILE, ALABAMA.

LOG-TURNER.

SPECIFICATION forming part of Letters Patent No. 338,669, dated March 23, 1886.

Application filed January 5, 1886. Serial No. 187,682. (No model.)

To all whom it may concern:

Be it known that I, WILLIAM INGALLS, a citizen of the United States, residing at Mobile, in the county of Mobile and State of Alabama, have invented certain new and useful Improvements in Log-Turners, of which the following is a specification, reference being had therein to the accompanying drawings.

This invention relates to improvements in log-turners, and has for its object to provide an efficient machine for turning logs in a saw-mill. This object is attained by the mechanism illustrated in the accompanying drawings, forming a part of this specification, in which—

15 Figure 1 is an elevation in which some of the parts are in section on the line $x-x$ of Fig. 2. Fig. 2 is a plan. Fig. 3 is an enlarged detached view of the double-pointed sprocket-wheel.

20 The letter A indicates the framing of a saw-mill. A' are cross-pieces, the ends of which rest thereon, and are placed a suitable distance apart to receive a frame, B, to the lower part of which is secured a shaft or axle, b, having 25 bearings in the boxes B', which are bolted to the cross-pieces A', upon which the frame B may be caused to oscillate, for a purpose hereinafter described. A vertical box or casing, C, extends from joists D of the mill in a downward direction between the cross-pieces A', and forms a receptacle for a weight, E, which is suspended by a chain or rope, F, which passes over a pulley, G, which turns upon a shaft, g, secured to the upper part of the box 30 C, and is carried under a pulley, H, secured to the frame B by means of the shaft I, having bearings in the boxes i, bolted to frame B. This chain F then passes over the top of a sprocket-wheel, J, having a double set of radial points, j, and provided with a shaft, K, which revolves in the boxes k, bolted to the upper end of the frame B. The chain F is then carried over the pulley L, then around the under part of said pulley to a windlass, M, 35 to which the end is secured. The pulley L has a shaft, l, which revolves in bearings N, secured to the frame B, which is also provided with a weight, B'. This weight B' is intended to cause the frame B to assume an inclined position, as shown in dotted lines in Fig. 1, after 40 the log O on the saw-carriage has been turned,

as this is necessary in order to take another hold of the log O, as well as to permit other logs, O', to be placed upon the saw-carriage. The chain F is maintained at the proper tension 55 by means of the weight E, which rises and falls in its casing C, according to the direction in which the windlass M is turned, by means of the pulley or crank M', for which purpose any suitable power—such as steam or water—60 may be used. Chocks P, attached to the frame of the saw-mill, support the upper end of the frame B when in an inclined position. When a log, O, has been placed upon a saw-carriage and is ready to be turned over, the windlass 65 M is put in motion by means of the pulley or crank M'. This gradually raises the frame B to a vertical position and causes the radial teeth j of the sprocket-wheel J to engage with the log O, and by continuing the motion of the 70 windlass the log is turned to the desired position.

Having described my invention, what I desire to secure by Letters Patent, and claim, is—

1. In a log-turner, the combination, with 75 the frame of a saw-mill, of an oscillating frame, of a sprocket-wheel revolving therein, said wheel having radial points adapted to engage with a saw-log, a tension-chain passing over 80 the top of said sprocket-wheel, one end of said chain attached to a weight and the other end secured to a windlass, substantially as described, and for the purposes set forth.

2. In a log-turner, the combination of box 85 C, of pulley G, of chain F, and weight E, with frame B, adapted to oscillate in bearings attached to the framing of a saw-mill, the said frame being provided with pulley H, the sprocket-wheel J, having double radial points 90 j, the pulley L, and windlass M, as described, and for the purposes set forth.

3. In a log-turner, the oscillating frame B, in combination with a sprocket-wheel, J, having double radial points j, as described, and 95 for the purposes set forth.

In testimony whereof I affix my signature in presence of two witnesses.

WM. INGALLS.
